Attest,

UNITED STATES PATENT OFFICE.

CHRISTIAN NELSON, OF PITTSBURG, PENNSYLVANIA.

CORK-MACHINE.

SPECIFICATION forming part of Letters Patent No. 482,212, dated July 15, 1890.

Application filed November 21, 1889. Serial No. 331,116. (No model.)

To all whom it may concern:

Be it known that I, CHRISTIAN NELSON, a citizen of the United States, residing at Pittsburgh, in the county of Allegheny and State of Pennsylvania, have invented certain new and useful Improvements in Cork-Machines; and I do hereby declare the following to be a full, clear, and exact description of the invention, such as will enable others skilled in the art to 5 which it pertains to make and use the same, reference being had to the accompanying drawings, which form a part of this specification.

My invention relates to an improved machine for making corks; and it consists in a frame having mounted thereon in suitable guides two carriages adapted to move at right angles to each other, a means for holding the blank piece of cork and releasing the same, and devices for moving the said carriages to 10 ward or along the face of a grinding-wheel, together with certain other details of construction and combination of parts, as will be fully set forth hereinafter.

In the accompanying drawings, Figure 1 is 15 a plan view of my improved machine. Fig. 2 is a sectional elevation of the same, partly shown in section.

To put my invention into practice I provide a frame *a*, of suitable size and form of construction, having formed in the direction of 20 its length the female portion *b* of a dovetail slide. Operating in this slide *b* is a carriage *c*, provided with a similar slide *d*, arranged in an opposite direction to that below and 25 provided with a second carriage *e*. Mounted on the top of this last-mentioned carriage *e*, in suitable bearings *f* *g*, are two short shafts *h* *i*, one of which is slightly bent to and secured in its bearing *f* by a set-screw *j*. This 30 shaft *h* may be moved in the direction of its length and held in any desired position by the set-screw *j*. On the inner end of this shaft *h* is loosely attached a clutch *k* for engaging with one end of the cork *l*. The other shaft 35 *i* is supported loosely in its bearings *g*, and is also provided with a clutch *m* for engaging with the cork *l*. Rigidly attached to this shaft *i* is a pulley-wheel *n* for giving the same a rotary movement by a suitable belt. About this 40 same shaft *i* is a coil-spring *o*, secured against a pin *p* and one of the bearings *g* in a manner that when the said shaft *i* is moved to re-

lease the cork *l* the same will recover or go back to its original position. Secured to one end of the lower carriage *c* by a pivot *q* is a 55 lever *r*, provided with an open slot *s*, which engages with an upwardly-projecting pin *t*, attached to the upper or top carriage *e* in a manner that the said carriage *e* and its several parts may be moved toward or away from 60 the flat face of a large grinding-wheel *u*. Attached to one end of the lower carriage *c* are two rods *v*, which move through two bearings *w*, against which the one end of two coil-springs *x* finds a bearing, the other ends of 65 these springs *x* resting against the carriage *c*. Attached to this same carriage *c* is a cord or chain *y*, which passes over a small roller *z* and then attached to a foot-treadle *a'*. This treadle *a'* when operated moves the carriages 70 *c* *e* in the direction of the length of the machine and are brought back to their former position by the two coil-springs *x*.

In operation the cork is cut in suitable lengths and a single piece placed between the 75 two clamps *k* *m*. By means of the lever *r* the said piece *l* is brought in contact with the side of a large grinding-wheel *u*, the shaft *i* is given a rotary motion, and the cork *l* ground circular in form and then removed by drawing the said shaft *i* back. This shaft *i* may 80 either be revolved by power or the same turned by hand by means of a small hand-wheel *b'*, secured to the outer end of the same.

In order to make a tapering cork, the entire 85 machine is canted or turned so that the carriages and the work clamped therein lie at an angle to the plane of the vertical working-surfaces on the grinding-wheel instead of being parallel therewith, as shown in Fig. 1, 90 and the machine, together with its carriages and several appliances, is secured in the desired position by bolts *c'*, passing through slots *d'*, formed in the ends of the frame *a*. The grinding-wheel *u* is provided on one of 95 its faces with annular sand-paper rings *e'*, as clearly shown in Fig. 2, each of which being of a different grade or degree of fineness, so that when the blank is first moved against a coarse ring the edges may be quickly removed 100 and then by means of the treadle the said cork moved along the face of the wheel *u* to finish the same on paper with a fine sand.

Having thus described my invention, what I

claim, and desire to secure by Letters Patent, is—

In a machine for grinding corks, the combination of an endwise-movable carriage *c*, a rotary grinding-disk arranged alongside of said carriage *c* with its lateral working-face adjacent thereto, springs for normally impelling the carriage *c* in one direction and substantially parallel with the lateral working-

face of said grinding-disk, a treadle connected to the carriage for moving the same in a contrary direction, another carriage *e* mounted on the carriage *c* to slide in a line at right angles to the movement of the carriage *c*, a lever

fulcrumed at one end on the carriage *c* and connected directly to the carriage *e* for moving the latter carriage at will toward or from the grinding-disk, and the rotary work-clamps mounted on the carriage *e*, as and for the purpose described.

In testimony that I claim the foregoing I hereunto affix my signature this 24th day of October, A. D. 1889.

CHRISTIAN NELSON. [L. S.]

In presence of—

M. E. HARRISON,
C. C. LEE.
